UNITED STATES PATENT OFFICE

HARRY LYON, OF BROCKTON, MASSACHUSETTS

PLANE FOR LEATHER AND THE LIKE

Application filed October 9, 1930. Serial No. 487,445.

This invention relates to planes particularly suitable for removing surface blemishes from leather, such as fleshy parts, wrinkles, scratches or stains, which heretofore have 5 been ordinarily removed by buffing. When the grain of the leather is thick as on the neck where wrinkles are likely to occur, a considerable thickness of material may be removed to remove the wrinkles without detriment. The device of this invention is also 10 useful when after splitting a shoulder it is found that the split layer is too thick for the splitting to have removed all of the fleshy parts. These fleshy parts may be removed 15 by means of the plane without requiring that the shoulder be run through the splitting machine a second time. For many purposes the slight inequality in thickness thus produced is immaterial.

In accordance with this invention the plane is provided with a cutting blade beveled at one edge and presented with its flat face at the long side of the bevel flat against the work. The relative softness of the 20 leather permits the blade to be pressed into the surface sufficiently to take a cut, the thickness of the shaving removed being regulated by a gage plate adjustable transversely of the face of the blade adjacent to its cutting edge.

For a more complete understanding of this invention, reference may be had to the accompanying drawing in which

Figures 1 and 2 are side and rear end elevations, respectively, of one form of this invention.

Figure 3 is a section on line 3—3 of Figure 2.

Figure 4 is a view similar to a portion 40 of Figure 3, but showing a different adjustment of the gage plate.

Figure 5 is a side elevation partly broken away showing a modified construction.

Figure 6 is a top plan of the construction 45 shown in Figure 5.

Figure 7 is a section on line 7—7 of Figure 5.

Referring first to Figures 1 to 4, at 1 is indicated a cutting blade having a beveled forward end 2 forming a cutting edge 3. The

side edges of the blade 1 are also beveled as shown at 4 for engagement in mating grooves 5 in the lower inner edges of the wall portions 6 of a semi-tubular handle member 7. When the blade is in position between the 55 wall portions 6 they are drawn together in clamping relation therewith by means of a threaded rod or tie member 8 extending through openings in the wall 6 and having nuts 9 on its outer ends. When the blade is 60 so clamped to the handle the plane of its lower face 10 at the long side of the bevel 2 is in alignment with the lower edges of the walls 6.

The forward end of the handle member 7 has fixed thereto a gage plate 12, adjustable vertically to move its lower edge 13 toward and away from the face 10 of the blade. For this reason it is shown as provided with slots 14 for the reception of fastening screws 15 which are threaded into the forward edges of the wall portion 6. This gage plate is positioned slightly forwardly of the cutting edge of the blade and the height of its lower edge from the plane of the lower face of the blade 1 determines the thickness of the shaving 20, which is cut by the blade. Leather being somewhat soft material, the blade which is presented with its face flat against the work may be pressed thereinto 75 sufficiently for its cutting edge to bite into the work and take a shaving. This shaving in this form of the device passes along the top face of the blade and escapes at the rear end of the handle 7.

In Figures 5, 6 and 7 a modified construction is shown in which the handle member 25 is provided with a forwardly and downwardly sloping front face 26 which extends down substantially to the upper face of the blade, the side wall portions 27 of the handle member which receive the blade therewith being extended forwardly of the lower edge of the wall portion 26 and adjustably supporting the gage 28 at their forward ends. As shown in Figure 5, these portions 27 may be extended forwardly above the plate 28 and be provided with adjusting screws 30 engaging the gage plate 28 adjacent to opposite ends and thereby form means for positively 85 90 95 100

moving the blade toward the lower face 10 of the blade 1, lock nuts 31 having been provided for securing these screws 30 in adjusted position. The face plate may be fixed in 5 adjusted position by tightening its securing screws 32, which pass through a slot 33 therein and are threaded into the forward ends of the portions 27.

The handle portion, at the wall 26 and the 10 rear end wall 35, may be cut as by the kerf 37 and opening 38, respectively, to cause the wall portions 27 to be resiliently held together so that they may be brought into 15 clamping relation to the cutting blade 1 by the tightening screw 39, which is shown as threaded in one side portion of the handle member as at 40 and provided with a head 41 at the opposite end having a screw driver slot 42 therein to facilitate tightening and 20 loosening. It will be noted that the plane so constructed has no portion projecting below the plane of the lower face of the blade where the cutting edge is located. Thus the plane may be presented flat against the work.

25 From the foregoing description of certain embodiments of this invention, it should be evident to those skilled in the art that various changes and modifications might be made without departing from the spirit or scope 30 of this invention as defined by the appended claims.

I claim:

35 1. A device of the class described comprising a blade having a beveled cutting edge at one end, a handle member having wall portions spaced to receive said blade with its side edges therebetween and with its face at the longer side of said bevel flush with the edges of said wall portion, and means for 40 clamping said wall portions against the edges of said blade.

45 2. A device of the class described comprising a blade having a beveled cutting edge at one end, a handle member having wall portions spaced to receive said blade with its side edges therebetween and with its face at the longer side of said bevel flush with the edges of said wall portion, means for clamping said 50 wall portions against the edges of said blade, and a gage plate bridging said wall members forwardly of said cutting edge and adjustable to move its lower edge toward and from the plane of said face.

55 3. A device of the class described comprising a flat blade having a beveled cutting edge at one end, a semi-tubular handle member having opposed wall portions formed to engage the side edges of said blade therebetween with its face at the longer side of the 60 bevel flush with the edges thereof, and a threaded tie member extending from one to the other of said wall portions above said blade for springing said wall portions into clamping relation thereto.

65 4. A device of the class described comprising

ing a flat blade having a beveled cutting edge at one end, a semi-tubular handle member having opposed wall portions formed to engage the side edges of said blade therebetween with its face at the longer side of the 70 bevel flush with the edges thereof, a threaded tie member extending from one to the other of said wall portions above said blade for springing said wall portions into clamping relation thereto, and a gage plate bridging 75 said walls at the forward end of said handle member adjacent to said cutting edge and spaced above the plane of said face.

5. A device of the class described comprising a blade having a beveled cutting edge at one end, a handle member having spaced wall portions for engagement with the side edges of said blade with their lower edges flush with the face of said blade at the longer face of said bevel, said handle member having a forward sloping face back from said cutting edge over which the chip cut by said blade may pass, and means to clamp said member to said blade.

6. A device of the class described comprising a blade having a beveled cutting edge at one end, a handle member having spaced wall portions for engagement with the side edges of said blade with their lower edges flush with the face of said blade at the longer face of said bevel, said handle member having a forward sloping face back from said cutting edge over which the chip cut by said blade may pass, means to clamp said member to said blade, and a gage plate carried by said member forwardly of said cutting edge and adjustable to present its lower edge a predetermined distance from the plane of said face.

105 In testimony whereof I have affixed my signature.

HARRY LYON.
